UNITED STATES PATENT OFFICE.

CHARLES CALHOUN RANKIN, OF LOUISVILLE, KENTUCKY, ASSIGNOR OF ONE-THIRD TO
SAMUEL T. CROFTS, OF LOUISVILLE, KENTUCKY.

PLOW.

No. 882,839.

Specification of Letters Patent. Patented March 24, 1908.

Application filed May 4, 1907. Serial No. 371,845.

To all whom it may concern:

Be it known that I, CHARLES CALHOUN RANKIN, a citizen of the United States, residing in the city of Louisville, county of 5 Jefferson, and State of Kentucky, have invented a new and useful Plow, of which the following is a specification.

My invention relates to improvements in plows, in which the principal parts are constructed of metal; and the objects of my improvement are, strength, lightness, compactness, simplicity, economy of labor, comparative inexpensiveness of manufacture, durability, to avoid the decay incident to 10 wood from the action of moisture and air, interchangeability of parts, facility of adjustment, and knock-down construction to facilitate storing, packing and shipping.

I attain these objects by means of the 20 structure illustrated in the accompanying drawings, in which—

Figure 1 is a perspective view of the plow with a straight, tubular beam of rectangular cross section; Fig. 2 is a perspective view of a 25 modification with a curved, tubular beam of circular cross section.

Similar reference numerals refer to similar parts throughout the several views of the drawings.

30 The tubular beam 1, the clamp 2, the clevis 3, the adjustable brace-clip 4, the brace 6, and the handle-clip 9 constitute the principal features of the invention. The beam 1 is tubular and may be square, round, 35 oval, elliptical or any other cross section. I prefer to make it of round tubing, preferably of steel, because it is cheapest.

In Fig. 1 a beam of square cross section is shown, and in Fig. 2 a beam of circular cross 40 section. In the modification shown in Fig. 2, the beam is slightly bent where the standard is attached, in order that a clamp conforming to the beam may be placed about it and the beam always remain in the same 45 relative position without turning either in use or when being assembled. A standard-clamp, 2, preferably made of two metal plates stamped or cast to conform to the exterior surface of the beam and the stand- 50 ard, is placed over the beam and standard

and clamped thereto by means of bolts 14 above and bolts 15 below. In Fig. 1 a regular standard is shown with clamp 2 embracing it and the beam.

In Fig. 2 a modification is shown wherein a 55 stock 13 is used instead of standard 13, and this stock is biparted and placed over clamp 2 instead of between the plates, a longer bolt 15 being used to secure the stock to the clamp. It will be understood that by this 60 means stock 13 is pivotally secured to clamp 2, so that its angle relative to the beam may be adjusted. The usual brace 6 is provided for taking the stress of standard 13. This brace is secured to the beam by means of an 65 adjustable brace-clip 4 and a clamp-bolt 5 at the lower part thereof as shown in the drawings. This brace may be placed either in front, as in Fig. 1, or in the rear, as in Fig. 2. Beam 1 being of tubing uniform in size and 70 shape throughout its length, clip 4 may be adjusted by sliding it along the beam and fastening it at any point. By this means the proper stress may be placed upon brace 6, and when the stock (Fig. 2) is used, it may be 75 adjusted at any angle relative to the beam desired. The moldboard 8 and the point 12 are of the conventional form. The clevis 3 is preferably cast of metal, hollow, so that it slips over the end of beam 1, and is slit on the 80 lower side and provided with bolt-holes, in order that it may be clamped firmly upon the beam. A handle-clip, 9, is provided, preferably cast of metal with a hollow portion conforming to the shape of beam 1, provided underneath with a slit and clamp-bolts 85 so that it may be clamped firmly on the rear end of the beam, and provided on the sides with clamp-sockets adapted to receive and firmly clamp tubular handles 10 and 11, or 90 formed with channels on the sides and bolt-holes adapted to receive wooden handles (Fig. 2) which may be bolted thereto.

It will be appreciated that all parts described may be easily made, and the plow 95 may be quickly assembled by unskilled labor and thus produced at a comparatively low price. The advantage in shipping and storing will also be apparent in as much as the several parts may be readily separated and 100

packed in small space, when shipped, and assembled by any one of ordinary skill.

I claim—

In a plow, the combination of a tubular beam, and a clevis, a standard fixture, and a handle-fixture clamped about said tubular beam to hold by friction only and adjust-

able at angles relative to the plane passing through the axis of said tubular beam.

CHARLES CALHOUN RANKIN.
